Primary Examiner — David G Muller*Assistant Examiner* — Christina Gabrielle Cosden(74) *Attorney, Agent, or Firm* — Gerald E. Hespos; Michael J. Porco**CLAIM**

The ornamental design for a ratchet locking device, as shown and described.

DESCRIPTION

FIG. 1 is a front, top, right perspective view of a ratchet locking device according to our new design;

FIG. 2 is a rear, top, left perspective view of a ratchet locking device shown in FIG. 1;

FIG. 3 is a front elevational view thereof;

FIG. 4 is a rear elevational view thereof;

FIG. 5 is a top view thereof;

FIG. 6 is a bottom view thereof;

FIG. 7 is a right side elevational view thereof; and,

FIG. 8 is a left side elevational view thereof.

The broken lines shown in the Figures are for illustrative purposes only and form no part of the claimed design.
